Primary Examiner—Stella Reid

[57] CLAIM

The ornamental design for an electromyogram muscle monitoring device, as shown and described.

DESCRIPTION

FIG. 1 is a top plan view of a first embodiment of an electromyogram muscle monitoring device, showing our new design;

FIG. 2 is a bottom view of FIG. 1;

FIG. 3 is a back view of FIG. 1;

FIG. 4 is a front view of FIG. 1;

FIG. 5 is a right side view of FIG. 1;

FIG. 6 is a left side view of FIG. 1;

FIG. 7 is a perspective view of FIG. 1 in open condition; and,

FIG. 8 is a perspective view of a second embodiment of the electromyogram muscle monitoring device in open condition, with the only difference residing in the size of the display screen.
